(57) **ABSTRACT**

A box can include a first side panel; a second side panel positioned perpendicular to the first side panel; a top panel joined to the first side panel; and a handle assembly, the handle assembly including: a handle portion attached to the top panel, the handle portion including a tab at a side end of the handle portion, and a locking panel attached to the second side panel, the locking panel defining a cut pattern, the cut pattern including a first side cut and a second side cut, a flap defined between the first side cut and the second side cut, the first side cut diverging into an inner cut extending along a bottom of the flap and an outer cut defining a space below the bottom of the flap, a portion of the second side cut extending along the bottom of the flap.

REFERENCE TO RELATED APPLICATIONS

This application is a continuation of U.S. application Ser. No. 17/887,093, filed Aug. 12, 2022, which is a continuation of U.S. application Ser. No. 17/339,278, filed Jun. 4, 2021, which issued as U.S. Pat. No. 11,447,286 on Sep. 20, 2022, which is a continuation of U.S. application Ser. No. 16/520,548, filed Jul. 24, 2019, which issued into U.S. Pat. No. 11,053,048 on Jul. 6, 2021, each of which is hereby specifically incorporated by reference herein in its respective entirety.

TECHNICAL FIELD

This disclosure relates to packaging. More specifically, this disclosure relates to a box with a foldable handle.

BACKGROUND

A box with a handle can be carried with one hand, facilitating its transport by retail customers. However, a handle on a box can interfere with stacking the boxes in a compact way.

SUMMARY

It is to be understood that this summary is not an extensive overview of the disclosure. This summary is exemplary and not restrictive, and it is intended to neither identify key or critical elements of the disclosure nor delineate the scope thereof. The sole purpose of this summary is to explain and exemplify certain concepts of the disclosure as an introduction to the following complete and extensive detailed description.

Disclosed is a box comprising: a first side panel; a second side panel positioned perpendicular to the first side panel; a top panel joined to the first side panel; and a handle assembly, the handle assembly comprising: a handle portion attached to the top panel, the handle portion comprising a tab at a side end of the handle portion, and a locking panel attached to the second side panel, the locking panel defining a cut pattern, the cut pattern comprising a first side cut and a second side cut, a flap defined between the first side cut and the second side cut, the first side cut diverging into an inner cut extending along a bottom of the flap and an outer cut defining a space below the bottom of the flap, a portion of the second side cut extending along the bottom of the flap, a bottom notch defined by the cut pattern between the outer cut and the portion of the second side cut

Also disclosed is a blank for a box comprising: a first side panel and a second side panel; a top panel joined to the first side panel; a handle portion attached to the top panel, the handle portion comprising a tab at a side end of the handle portion; and a locking panel attached to the second side panel, the locking panel defining a cut pattern, the cut pattern comprising a first side cut and a second side cut, a flap defined between the first side cut and the second side cut, the first side cut diverging into an inner cut extending along a bottom of the flap and an outer cut defining a space below the bottom of the flap, a portion of the second side cut extending along the bottom of the flap, a bottom notch defined by the cut pattern between the outer cut and the portion of the second side cut

Various implementations described in the present disclosure may include additional systems, methods, features, and

2

advantages, which may not necessarily be expressly disclosed herein but will be apparent to one of ordinary skill in the art upon examination of the following detailed description and accompanying drawings. It is intended that all such systems, methods, features, and advantages be included within the present disclosure and protected by the accompanying claims. The features and advantages of such implementations may be realized and obtained by means of the systems, methods, features particularly pointed out in the appended claims. These and other features will become more fully apparent from the following description and appended claims, or may be learned by the practice of such exemplary implementations as set forth hereinafter.

15 BRIEF DESCRIPTION OF THE DRAWINGS

The features and components of the following figures are illustrated to emphasize the general principles of the present disclosure. The drawings are not necessarily drawn to scale.

20 Corresponding features and components throughout the figures may be designated by matching reference characters for the sake of consistency and clarity.

FIG. 1 is a perspective view of a box with a foldable handle in accordance with one aspect of the present disclosure, wherein the handle is in an upright configuration.

FIG. 2 is a perspective view of the box of FIG. 1, wherein the handle is in a folded-down configuration.

FIG. 3 is a perspective view of the box of FIG. 1, wherein a handle assembly is disassembled.

30 FIG. 4 is a cross-section of the box of FIG. 1, taken along line 5-5 in FIG. 1.

FIG. 5 is a perspective view of the box of FIG. 1 in a collapsed configuration.

FIG. 6 is a top view of a box blank for the box of FIG. 1.

35 FIG. 7 is a view of a first handle portion of the box blank of FIG. 6.

FIG. 8 is a view of a second handle portion of the box blank of FIG. 6.

FIG. 9 is view facing a locking panel of the box of FIG.

40 1.

FIG. 10 is a perspective view of the box of FIG. 1, wherein the handle assembly of FIG. 3 is partially-assembled.

FIG. 11 is a perspective view of one end of the handle assembly of FIG. 3, wherein the handle of FIG. 1 is in an upright position.

45 FIG. 12 is a perspective view of the handle assembly of FIG. 3, wherein the handle of FIG. 1 is partially folded down.

50 DETAILED DESCRIPTION

The present disclosure can be understood more readily by reference to the following detailed description, examples, 55 drawings, and claims, and the previous and following description. However, before the present devices, systems, and/or methods are disclosed and described, it is to be understood that this disclosure is not limited to the specific devices, systems, and/or methods disclosed unless otherwise specified, and, as such, can, of course, vary. It is also to be understood that the terminology used herein is for the purpose of describing particular aspects only and is not intended to be limiting.

60 The following description is provided as an enabling teaching of the present devices, systems, and/or methods in its best, currently known aspect. To this end, those skilled in the relevant art will recognize and appreciate that many

changes can be made to the various aspects of the present devices, systems, and/or methods described herein, while still obtaining the beneficial results of the present disclosure. It will also be apparent that some of the desired benefits of the present disclosure can be obtained by selecting some of the features of the present disclosure without utilizing other features. Accordingly, those who work in the art will recognize that many modifications and adaptations to the present disclosure are possible and can even be desirable in certain circumstances and are a part of the present disclosure. Thus, the following description is provided as illustrative of the principles of the present disclosure and not in limitation thereof.

As used throughout, the singular forms "a," "an" and "the" include plural referents unless the context clearly dictates otherwise. Thus, for example, reference to "an element" can include two or more such elements unless the context indicates otherwise.

Ranges can be expressed herein as from "about" one particular value, and/or to "about" another particular value. When such a range is expressed, another aspect includes from the one particular value and/or to the other particular value. Similarly, when values are expressed as approximations, by use of the antecedent "about," it will be understood that the particular value forms another aspect. It will be further understood that the endpoints of each of the ranges are significant both in relation to the other endpoint, and independently of the other endpoint.

For purposes of the current disclosure, a material property or dimension measuring about X or substantially X on a particular measurement scale measures within a range between X plus an industry-standard upper tolerance for the specified measurement and X minus an industry-standard lower tolerance for the specified measurement. Because tolerances can vary between different materials, processes and between different models, the tolerance for a particular measurement of a particular component can fall within a range of tolerances.

As used herein, the terms "optional" or "optionally" mean that the subsequently described event or circumstance can or cannot occur, and that the description includes instances where said event or circumstance occurs and instances where it does not.

The word "or" as used herein means any one member of a particular list and also includes any combination of members of that list. Further, one should note that conditional language, such as, among others, "can," "could," "might," or "may," unless specifically stated otherwise, or otherwise understood within the context as used, is generally intended to convey that certain aspects include, while other aspects do not include, certain features, elements and/or steps. Thus, such conditional language is not generally intended to imply that features, elements and/or steps are in any way required for one or more particular aspects or that one or more particular aspects necessarily include logic for deciding, with or without user input or prompting, whether these features, elements and/or steps are included or are to be performed in any particular aspect.

Disclosed are components that can be used to perform the disclosed methods and systems. These and other components are disclosed herein, and it is understood that when combinations, subsets, interactions, groups, etc. of these components are disclosed that while specific reference of each various individual and collective combinations and permutation of these may not be explicitly disclosed, each is specifically contemplated and described herein, for all methods and systems. This applies to all aspects of this applica-

tion including, but not limited to, steps in disclosed methods. Thus, if there are a variety of additional steps that can be performed it is understood that each of these additional steps can be performed with any specific aspect or combination of aspects of the disclosed methods.

The use of the directional terms herein, such as right, left, front, back, top, bottom, and the like can refer to the orientation shown and described in the corresponding figures, but these directional terms should not be considered limiting on the orientation or configuration required by the present disclosure. The use of ordinal terms herein, such as first, second, third, fourth, and the like can refer to elements associated with elements having matching ordinal numbers. For example, a first light bulb can be associated with a first light socket, a second light bulb can be associated with a second light socket, and so on. However, the use of matching ordinal numbers should not be considered limiting on the associations required by the present disclosure.

The box disclosed herein can comprise structure, such as side panels, shoulders, and bottom panels, similar to those described in the following application: U.S. patent application Ser. No. 15/845,545, filed Dec. 18, 2017, entitled "Modular Box Assembly." This application is hereby incorporated by reference in its entirety.

Disclosed is a box with a foldable handle and associated methods, systems, devices, and various apparatus. It would be understood by one of skill in the art that the box is described in but a few exemplary embodiments among many. No particular terminology or description should be considered limiting on the disclosure or the scope of any claims issuing therefrom. Terms used in the present disclosure can refer to identical terms in the incorporated references.

FIG. 1 is a perspective view of a box 101 with a foldable handle 170, with the handle 170 in an upright configuration. The handle 170 can be a part of a handle assembly 82, the handle assembly 82 further comprising locking panels 84. The locking panels 84 can comprise top corners 954, discussed further with respect to FIG. 9. The handle 170 can comprise two handle portions 85, each handle portion 85 comprising two side ends 86, each side end 86 secured by one of the locking panels 84 when the handle 170 is in the upright configuration. Line 5-5 defines a cross-sectional view, which is shown in FIG. 4. In one aspect, the box 101 can be adjustable about and between an expanded configuration (illustrated in FIG. 1) in which the box 101 has an expanded volume, and a collapsed configuration (illustrated in FIG. 5) in which the box 101 has a collapsed volume that is less than the expanded volume. The box 101 can comprise a rigid board material such as corrugated cardboard; however in other aspects, the box can comprise other suitable rigid board materials, such as wood, plastic, metal, or any other material.

The box 101 can comprise a first pair of opposing side panels 112a,b (112b not shown) and a second pair of opposing side panels 122a,b (122a not shown). That is, the box 101 can comprise a first side panel 112a, a second side panel 112b opposed to the first side panel, 112a a third side panel 122a positioned between the first side panel 112a and the second side panel 112b, and a fourth side panel 122b opposed to the third side panel 122a and positioned between the first and second side panels 112a,b. The side panels 112a,b, 122a,b can each be a rigid panel. In one aspect, the side panel 112a can be substantially parallel to the side panel 112b, and the side panel 122a can be substantially parallel to the side panel 122b. Each of the first pair of side panels 112a,b can be substantially perpendicular to the second pair

of side panels 122a,b. In one aspect, the box 101 can define a rectangular or square cross-sectional shape, as shown in FIG. 4; however, in other aspects, the box 101 can define a different cross-sectional shape such as a circular, triangular, pentagonal, or hexagonal, shape or any other desired shape.

FIG. 2 is a perspective view of the box 101 of FIG. 1, wherein the handle 170 is in a folded-down configuration. The handle assembly 82 is discussed in further detail below. One of the top corners 954 of each locking panel 84 can be inserted into a securing cut 610 of a top panel 602, as discussed further with respect to FIG. 6 and FIG. 12. In the folded-down configuration, an upper surface 202 of the box 101 can be substantially planar, such that a plurality of the boxes 101 can be stacked on each other.

FIG. 3 is a perspective view of the box 101 of FIG. 1, wherein the handle assembly 82 is disassembled. The box 101 can define a box opening 106 at a top end 102 thereof. The first pair of opposing side panels 112a,b and the second pair of opposing side panels 122a,b of the box 101 can define a box cavity 206. A pair of shoulders 222a,b can extend inwards into the box cavity 206 from each of the side panels 122a,b, as represented by the shoulder 222a (shoulder 222b shown in FIG. 4).

FIG. 4 is a cross-section of the box 101 of FIG. 1 taken along line 5-5 shown in FIG. 1, with the handle 170 removed. In one aspect, each shoulder 222a,b can comprise two sub-shoulders 322. The shoulder 222a can comprise sub-shoulders 322a,b, and the shoulder 222b can comprise sub-shoulders 322c,d. The sub-shoulders 322a-d can be defined by a plurality of first wings 312a-d and a plurality of second wings 324a-d. The first wings 312a,b can be attached at opposite sides of the side panel 112a, and the first wings 312c,d can be attached at opposite sides of the side panel 112b. The second wings 324a,b can be attached at opposite sides of the side panel 122a, and the second wings 324c,d can be attached at opposite sides of the side panel 122b.

The second wing 324a can be folded inwards at a hinge 365a and positioned adjacent to an inner side surface 326a of the side panel 122a, and the first wing 312c can be folded at a hinge 370c and positioned adjacent to the second wing 324a. The second wing 324a and the first wing 312c can be secured in position, such as with an adhesive, to form the sub-shoulder 322a. The second wing 324b can be folded inwards at a hinge 365b and positioned adjacent to the inner side surface 326a, and the first wing 312a can be folded at a hinge 370a and positioned adjacent to the second wing 324b. The second wing 324b and the first wing 312a can be secured in position, such as with an adhesive, to form the sub-shoulder 322b.

To form the sub-shoulder 322c of shoulder 222b, the second wing 324c can be folded inward at a hinge 365c and positioned adjacent to an inner side surface 326b of the side panel 122b. The first wing 312d can be folded at a hinge 370d and positioned adjacent to the second wing 324c. The first wing 312d and the second wing 324c can be secured in position, such as with an adhesive, to form the sub-shoulder 322c. To form the sub-shoulder 322d of shoulder 222b, the second wing 324d can be folded inward at a hinge 365d and positioned adjacent to the inner side surface 326b. The first wing 312b can be folded at a hinge 370b and positioned adjacent to the second wing 324d. The first wing 312b and the second wing 324d can be secured in position, such as with an adhesive, to form the sub-shoulder 322d.

The formation of the sub-shoulders 322a-d can also secure each of the first pair of side panels 112a,b to each of the second pair of side panels 122a,b, thereby defining the square or rectangular horizontal cross-section of the box

101. In one aspect, the box 101 can further comprise a bottom panel 306. The bottom panel 306 can be a rigid panel. The bottom panel 306 can be disposed at the bottom end 104 of the box 101, and the bottom panel 306 can be attached to each of the side panels 112a,b, 122a,b. The bottom panel 306 can further define the box cavity 206.

In the present aspect, the bottom panel 306 can define a center subpanel 380 disposed substantially at a center of the bottom panel 306. The center subpanel 380 can be substantially rectangular in shape. In the collapsed configuration, the rectangular-shaped center subpanel 380 in one aspect can define a width that matches a thickness of the collapsed box, thereby relieving pressure from the fold lines of the bottom panel 306.

15 A center fold line 382 such as, for example, a scored crease, can extend between the center subpanel 380 and each side panel 112a,b, and the center fold line 382 can substantially bisect the bottom panel 306, with the exception of within the center subpanel 380. The center fold line 382 can 20 also bisect each side panel 112a,b, as shown and further described with respect to FIG. 9. In one aspect, and with respect to FIG. 6, the center fold line 382 can comprise a double center fold line 382. That is, the center fold line can comprise at least a first center fold line 382a and a second center fold line 382b positioned adjacent to each other. In this aspect, the center fold line 382 can comprise two substantially parallel fold lines spaced a predetermined distance apart. In another aspect, the distance between the center fold lines 382a,b can be less than a width of the center subpanel 380.

25 In one aspect, four corner fold lines 384a-d can extend between the corners of the center subpanel 380 and the hinges 370a-d. For example, a first corner fold line 384a can extend from a first hinge 370a to the center subpanel 380, a second corner fold line 384b can extend from a second hinge 370b to the center subpanel 380, a third corner fold line 384c can extend from a third hinge 370c to the center subpanel 380 and a fourth corner fold line 384d can extend from a fourth hinge 370d to the center subpanel 380.

30 40 A plurality of V-shaped fold lines 386a-h can extend between the hinges 370a-d and the center fold line 382. In one aspect, the V-shaped fold lines 386a-d can each extend from the first hinge 370a to the center fold line 382 and then to the second hinge 370b. The V-shaped fold lines 386a-d can be defined between the corner fold lines 384a and 384b. The V-shaped fold lines 386e-h can each extend from the third hinge 370c to the center fold line 382 and then to the fourth hinge 370d. The V-shaped fold lines 386e-h can be defined between the corner fold lines 384c and 384d. In use, the center subpanel 380, the center fold line 382, the corner fold lines 384a-d, and the V-shaped fold lines 386a-h can cooperate to collapse the box 101. Optionally, the center subpanel 380, the center fold line 382, the corner fold lines 384a-d, and the V-shaped fold lines 386a-h can provide the bottom panel with a truncated pyramidal shape when collapsed, as further discussed below with respect to FIG. 5.

45 55 FIG. 5 is a perspective view of the box 101 of FIG. 1 in a collapsed configuration. As the box 101 collapses, the side panels 122a,b move inwards and towards one another (122a shown in FIG. 3), and the side panels 112a,b (112b shown in FIG. 3) fold inwards towards one another. The V-shaped fold lines 386a-h (shown in FIG. 4) cooperate to transition the bottom panel 306 from a substantially planar shape to the truncated pyramidal shape. In the truncated pyramidal shape, the center subpanel 380 extends outwards and away from the side panels 112a,b and the side panels 122a,b. Exerting a force upon the center subpanel 380, such as by

positioning the center subpanel on a surface and urging the side panels **112a,b**, **122a,b** towards the center subpanel **380** can cause the box **101** to self-expand into an expanded configuration (shown in FIG. 1) with a substantially rectangular prism shape. The self-expanding action can be desirable to allow for quick and easy reconfiguration of the box **101**, unlike many boxes which must be folded and taped together. The box **101** can be shipped and stored in the collapsed configuration for space-efficient packing, and a user can simply press upon the center subpanel **380**, such as by pressing the center subpanel **380** against the ground, and the box **101** can reconfigure to the expanded configuration.

FIG. 6 is a top view of a blank **710** for the box **101** of FIG. 1. In the current aspect, the blank **710** can comprise the two handle portions **85**, such as a first handle portion **85a** and a second handle portion **85b**. The first and the second handle portions **85a,b** can be joined to top panels **602**, such as a first and a second top panel **602a,b**, respectively, by a fold line **604**. The first and the second top panels **602a,b** can be joined to the third and the fourth side panels **122a,b**, respectively, by fold lines **606**. The locking panels **84**, such as a first and a second locking panel **84a,b**, can be joined to the first and the second side panels **112a,b** by a fold line **608**.

The second top panel **602b** can comprise two securing cuts **610**. Each securing cut **610** can define a perimeter **612**, the perimeter **612** defined by a fold line **614**, a length cut **616** opposite the fold line **618**, and two side cuts **620** connecting the length cut **616** and the fold line **614**. Each side cut **620** can be curvilinear, such that the side cuts **620** and the fold line **614** form an approximate half circle, wherein the length cut **616** forms a diameter of the half circle. The length cut **616** can be angled with respect to a side edge **622** of the top panel **602b**. For example, the length cut **616** and the side edge **622** can form a 45-degree angle.

In one aspect, the box blank **710** can define four corner fold lines **750a-d**, such as a scored crease. In other aspects, the box blank **710** can define cuts in place of the corner fold lines **750a-d**. A first corner fold line **750a** can extend outwards from the bottom panel **306** to separate the first wing **312a** from the second wing **324b**. A second corner fold line **750b** can extend outwards from the bottom panel **306** to separate the first wing **312b** from the second wing **324d**. A third corner fold line **750c** can extend outwards from the bottom panel **306** to separate the first wing **312c** from the second wing **324a**. A fourth corner fold line **750d** can extend outwards from the bottom panel **306** to separate the first wing **312d** from the second wing **324c**. In the present aspect, the adjacent first wings **312a-d** and first wings **324a-d** can be hingedly connected by the corner fold lines **750a-d**. In other aspects, the corner fold lines **750a-d** can be cuts which separate the adjacent first wings **312a-d** and second wings **324a-d**.

In one aspect, the box blank **710** can further define a first length fold line **712a** and a second length fold line **712b** extending from the side panel **112a** to the side panel **112b**. The first length fold line **712a** can facilitate folding of the first wing **312a** relative to the side panel **112a**, the side panel **122a** relative to the bottom panel **306**, and the first wing **312c** relative to the second side panel **112b**. The second length fold line **712b** can facilitate folding of the first wing **312b** relative to the side panel **112a**, the side panel **122b** relative to the bottom panel **306**, and the first wing **312d** relative to the side panel **112b**.

The box blank **710** can further define a first width fold line **722a** and a second width fold line **722b**. In one aspect, the width fold lines **722a,b** can be substantially perpendicular to the length fold lines **712a,b**. The first width fold line **722a**

can facilitate folding of the second wing **324a** relative to the side panel **122a**, the side panel **112b** relative to the bottom panel **306**, and the second wing **324c** relative to the side panel **122b**. The second width fold line **722b** can facilitate folding of the second wing **324b** relative to the side panel **122a**, the side panel **112a** relative to the bottom panel **306**, and the second wing **324d** relative to the side panel **122b**.

The center fold line **382** can extend across and substantially bisect each side panel **112a,b**. In one aspect, the center fold line can facilitate each of the side panels **112a,b** folding inwards about the center fold line **382** and towards the bottom panel **306** to facilitate collapsing the box **101** as shown in FIG. 5. If the center fold line comprise a double center fold line **382a,b**, as illustrated in FIG. 6, the center fold lines can facilitate each of the side panels **112a,b** more easily folding inwards about the first center fold line **382a** and the second center fold line **382b** and towards the bottom panel **306** to facilitate collapsing the box **101**.

FIG. 7 is a view of the first handle portion **85a** of the box blank **710**. Each handle portion **85** can comprise a side end **86**, such as a first side end **86a** and a second side end **86b**. Each side end **86** can comprise a tab **702**, the tab **702** defining a perimeter edge **704**. The perimeter edge **704** of the tab **702** can comprise a corner **706** extending laterally past the side edge **622** of the adjoining top panel **602**. From the corner **706**, the perimeter edge **704** can comprise a straight lateral edge **708** that extends away from the top panel **602** in a direction parallel to the side edge **622** of the top panel **602**. From the lateral edge **708**, the tab perimeter edge **704** can continue along a curvilinear corner **712** and a top edge **714**. The perimeter edge **704** can continue from the tab top edge **714** to an inner side edge **716** of the tab **702**. The inner side edge **716** can end in a notch **718** between the inner side edge **716** and a middle portion **720** of the handle portion **85**. The middle portion **720** can comprise a top edge **722** and a sloped edge **724** between the top edge **722** and the tab **702**, the sloped edge **724** meeting the tab **702** at the notch **718**.

The handle portion **85a** can define a handle cut **726** adjacent to the fold line **604**. The handle cut **726** can comprise a top edge **728**, two curvilinear top corners **730**, and two side edges **732**. In some aspects, the handle cut **726** can lack a bottom edge, such as on a first handle cut **726a** on the first handle portion **85a** of FIG. 7. When the blank **710** (shown in FIG. 6) is assembled into the box **101** (shown in FIG. 1), the first handle portion **85a** can fold approximately perpendicular to the first top panel **602a**. As such, a handle hole flap **734**, defined on its outside edge by the handle cut **726**, can fold and remain coplanar with the top panel **602**, such that the flap **734** is also perpendicular to the handle portion **85**, and the configuration can reveal a handle hole **804** (shown in FIG. 8).

FIG. 8 is a view of the second handle portion **85b** of the box blank **710**. The second handle portion **85b** can define a second handle cut **726b**, the second handle cut **726b** further comprising a bottom edge **802** that is a bottom cut, such that the handle hole **804** is exposed even in a flat configuration.

FIG. 9 shows one of the locking panels **84**. The locking panel **84** can comprise a top edge **950** and two side edges **952**, the top edge **950** and the side edges **952** meeting at two curvilinear top corners **954**. The locking panel **84** can define a handle-engaging cut pattern **902**. The parts of the cut pattern **902** are first described and labeled in FIG. 9. The cut pattern **902** can define a top hole **904**. The top hole **904** can be an oval, for example and without limitation. A fold line **906** can horizontally bisect the top hole **904**. Following the cut pattern **902** clockwise, as oriented in FIG. 9, the fold line **906** can meet a first corner cut **908a** which slopes down until

it meets a first side cut 910a (on the right side of FIG. 9). The first corner cut 908a can slope toward a bottom corner 951 of the locking panel 84, the bottom corner 951 located at an intersection of the locking panel 84, the attached side panel 112, and one of the side panels of the second pair of side panels 122 (not shown) when in the assembled configuration.

Approximately halfway down the first side cut 910a, the cut pattern 902 can separate into an inner cut 912 bordering an inner flap 914 and an outer cut 916 outlining a space 918 through which the handle tab 702 (not shown) can be received. Continuing clockwise from a point 920 where the inner cut 912 and the outer cut 916 separate, the inner cut 912 extends horizontally (to the left) along an inner flap bottom cut 922 toward a second side cut 910b. The second side cut 910b can meet a second corner cut 908b, the second corner cut 908b meeting the fold line 906 at a second meeting point 924b opposite a first meeting point 924a where the fold line 906 meets the first corner cut 908a. The inner flap 914 can have reflection symmetry about vertical line 926-926. A segment 928 of the center fold line 382 along line 926-926 can extend from the side panels 112 to the locking panel 84.

Continuing along the outer cut 916 in a clockwise direction (still with respect to FIG. 9) from the point 920, the first side cut 910a continues down until it meets a first bottom cut 930 that extends horizontally until meeting a bottom notch 932 along line 926-926. The bottom notch 932 can be a half circle. The bottom notch 932 can adjoin a vertical edge 934 that extends up to meet the inner flap 914 proximate to the line 926-926. At a point 936 where the vertical edge 934 meets the inner flap 914, the outer cut 916 can join the inner cut 912, such that continuing clockwise around the cut pattern 902, both the inner cut 912 and the outer cut 916 follow the flap bottom cut 922 to meet the second side cut 910b. The cut pattern 902 on one of the locking panels 84 can be a mirror image of the cut pattern 902 on the opposing locking panel 84.

FIG. 10 is a perspective view of the box 101, wherein the handle assembly 82 is partially-assembled. In the current aspect, the first and the second top panels 602a,b can fold down to form a top surface 1002 of the box 101. The handle hole flap 734 of the first handle portion 85a (hidden behind second handle portion 85b) can pass through the handle hole 804 of the second handle portion 85b. The handle hole flap 734 can press against the second top panel 602b to provide stability to the top surface 1002. The bottom notch 932 (shown in FIG. 9) of the cut pattern 902 can receive the tab corners 706 of the handle portions 85a,b, preventing the top surface 1002 from depressing further into the box 101.

The inner flaps 914 of the locking panels 84 can fold up and inward toward a center 1010 of the box 101. As such, the top hole 904 (shown in FIG. 9) can fold in half, onto itself, revealing a top notch 1006 (shown in FIG. 12). The fold line 906 (shown in FIG. 9) bisecting the top hole 904 can be a top edge 1004 in this configuration. The locking panels 84 can fold towards the center 1010, such that the top notch 1006 (shown in FIG. 11) of each locking panel 84 can slide over the top edge 714 of the handle tab 702 and receive the handle notch 718.

FIG. 11 is a perspective view of one side of the handle assembly 82 in an assembled configuration, wherein the handle 170 is in an upright position. The top notch 1006 of the cut pattern 902 can meet or contact the handle notch 718. As such, the box 101 can be picked up by the handle 170, the locking panels 84 preventing the handle portions 85 from separating.

FIG. 12 is a perspective view of the handle assembly 82 of the box 101, wherein the handle 170 is partially folded down. The vertical edge 934 of the bottom notch 932 can prevent the handle 170 from folding down in one direction (such as to the right, as shown in FIG. 12). The handle 170 can fold down in a direction opposite the vertical edge 934. As the handle 170 folds down, the handle notch 718 can engage the outer cut 916 of the cut pattern 902, such that the locking panels 84 are pulled down to the top surface 1002 (shown in FIG. 10) of the box 101 with the handle 170. In the folded-down configuration, the notches 718 of the handle portion 85 can touch or be proximate to a point where the first corner cut 908a meets the first side cut 910a. One of the top corners 954 of each locking panel 84 can be inserted into one of the securing cuts 610 (shown in FIG. 2) of the top panel 602, as shown in FIG. 2. As such, the locking panels 84 can hold down the handle 170 in the folded-down configuration. In this configuration, a plurality of the boxes 101 can be stacked compactly—for example, in a retail display area. When a customer wishes to purchase one of the boxes 101, they can easily pop the locking panels 84 out of the securing cuts 610, raise the handle 170 to the upright configuration, and carry box 101 by the handle 170 with one hand.

One should note that conditional language, such as, among others, "can," "could," "might," or "may," unless specifically stated otherwise, or otherwise understood within the context as used, is generally intended to convey that certain embodiments include, while other embodiments do not include, certain features, elements and/or steps. Thus, such conditional language is not generally intended to imply that features, elements and/or steps are in any way required for one or more particular embodiments or that one or more particular embodiments necessarily include logic for deciding, with or without user input or prompting, whether these features, elements and/or steps are included or are to be performed in any particular embodiment.

It should be emphasized that the above-described embodiments are merely possible examples of implementations, merely set forth for a clear understanding of the principles of the present disclosure. Any process descriptions or blocks in flow diagrams should be understood as representing modules, segments, or portions of code which include one or more executable instructions for implementing specific logical functions or steps in the process, and alternate implementations are included in which functions may not be included or executed at all, may be executed out of order from that shown or discussed, including substantially concurrently or in reverse order, depending on the functionality involved, as would be understood by those reasonably skilled in the art of the present disclosure. Many variations and modifications may be made to the above-described embodiment(s) without departing substantially from the spirit and principles of the present disclosure. Further, the scope of the present disclosure is intended to cover any and all combinations and sub-combinations of all elements, features, and aspects discussed above. All such modifications and variations are intended to be included herein within the scope of the present disclosure, and all possible claims to individual aspects or combinations of elements or steps are intended to be supported by the present disclosure.

That which is claimed is:

1. A box comprising:
a first side panel;
a second side panel positioned perpendicular to the first side panel;

11

a top panel comprising a securing cut and coupled to the first side panel; and
 a handle assembly configurable between an upright configuration and a folded-down configuration, the handle assembly comprising:
 a handle portion coupled to the top panel and comprising a side end defining a tab, and
 a locking panel wherein:
 in the upright configuration, a cut pattern of the locking panel engages the handle portion, and the second side panel is positioned perpendicular to the handle portion; and
 in the folded-down configuration, a corner of the locking panel is inserted into the securing cut of the top panel.

2. The box of claim 1, wherein the handle portion of the handle assembly further comprises a handle notch, wherein in the folded-down configuration, the locking panel holds down the handle portion in a substantially flat configuration, and in the upright configuration, the handle notch is received by the locking panel and the handle assembly is raised to carry the box.

3. The box of claim 1, wherein in the folded-down configuration, the top panel and the handle assembly define a substantially planar upper surface of the box.

4. The box of claim 1, wherein the top panel comprises two securing cuts for two corners of the locking panel to secure the handle assembly in the folded-down configuration.

5. The box of claim 1, wherein in the upright configuration, the tab is received by a space within a flap folded about a fold line, the handle portion defines a handle notch adjacent to the tab, and wherein the handle notch engages a top notch defined by the fold line.

6. The box of claim 1, wherein the securing cut in the top panel defines a perimeter defined by a fold line, a length cut disposed opposite the fold line, and two side cuts connecting the length cut and the fold line.

7. The box of claim 6, wherein each side cut of the securing cut is curvilinear and defines a circular portion, and the length cut forms a diameter of the circular portion.

8. The box of claim 6, wherein the length cut is angled with respect to a side edge of the top panel.

9. The box of claim 6, wherein the length cut forms a 45-degree angle with respect to a side edge of the top panel.

10. The box of claim 1, wherein the locking panel of the handle assembly further comprises:

a flap folded about a fold line comprising a handle notch of the handle portion;
 a first side cut diverging into an inner cut extending along a bottom of the flap and an outer cut defining a space below the bottom of the flap;
 a second side cut, wherein a portion of the second side cut extends along the bottom of the flap, wherein the fold line is defined between the first side cut and the second side cut; and
 a bottom notch defined by the cut pattern between the outer cut and the portion of the second side cut.

11. The box of claim 10, wherein the tab is received by the space with the flap folded about the fold line and the handle portion defines the handle notch adjacent to the tab, and

12

wherein in the upright configuration, the handle notch engages a top notch defined by the fold line.

12. The box of claim 10, wherein the inner cut and the portion of the second side cut form a linear flap bottom cut.

13. The box of claim 10, wherein the inner cut is parallel to the outer cut and the portion of the second side cut is parallel to the outer cut.

14. The box of claim 10, wherein the cut pattern defines a vertical edge extending upwards from the bottom notch to the portion of the second side cut.

15. The box of claim 14, wherein the vertical edge is perpendicular to the portion of the second side cut and the vertical edge is perpendicular to the inner cut.

16. The box of claim 1, wherein the locking panel defines a handle-engaging cut pattern comprising a top hole.

17. The box of claim 16, wherein the handle-engaging cut pattern comprises a bottom notch opposite the top hole.

18. A method of assembling a box, comprising:
 folding a first side panel relative to a second side panel positioned perpendicular to the first side panel;
 folding a top panel from the first side panel, the top panel comprising a securing cut; and
 folding a handle assembly between an upright configuration and a folded-down configuration, wherein the handle assembly comprises
 a handle portion coupled to the top panel and comprising a side end defining a tab, and
 a locking panel, wherein:

in the upright configuration, a cut pattern of the locking panel engages the handle portion, and the second side panel is positioned perpendicular to the top panel; and
 in the folded-down configuration, a curvilinear top corner of the locking panel is inserted into the securing cut of the top panel.

19. The method of claim 18, wherein folding the handle assembly into the folded-down configuration comprises securing the handle portion within the locking panel, and folding the handle assembly into the upright configuration comprises securing a handle notch within the locking panel and raising the handle assembly to carry the box.

20. The method of claim 18, wherein folding the handle assembly into the folded-down configuration defines a substantially planar upper surface of the box.

21. The method of claim 18, wherein folding the handle assembly into the folded-down configuration comprises securing cuts a pair of top corners of the locking panel within a pair of securing cuts to secure the locking panel of the handle assembly in the folded-down configuration.

22. The method of claim 18, wherein folding the handle assembly in the upright configuration comprises inserting the handle portion into the locking panel, and wherein folding the handle assembly in the folded-down configuration comprises inserting the locking panel into the securing cut of the top panel.

23. The method of claim 18, wherein the handle portion defines a handle tab and a handle notch, and wherein orienting the handle portion in the upright configuration further comprises sliding the locking panel over a top edge of the handle tab to receive the handle notch.
